(57) **CLAIM**

The ornamental design for a window section, as shown and described.

DESCRIPTION

FIG. 1 is an elevated rear perspective view of a window section, the broken line showing of the vehicle and tool being for illustrative purposes only, and forms no part of the claimed design.

FIG. 2 is an enlarged side view of the window section design of FIG. 1.

FIG. 3 is an enlarged rear view of the window section design of FIG. 1.

FIG. 4 is an enlarged front view of the window section design of FIG. 1.

FIG. 5 is an enlarged top view of the window section design of FIG. 1; and,

FIG. 6 is an enlarged bottom view of an window section design of FIG. 1.
